UNITED STATES PATENT OFFICE.

JOHN KREIBICH, OF PHILADELPHIA, PENNSYLVANIA.

SPRING-CONTROLLED DRAW-OFF COCK FOR LIQUID-CONTAINERS.

986,070.

Specification of Letters Patent.

Patented Mar. 7, 1911.

Application filed September 23, 1910. Serial No. 583,359.

To all whom it may concern:

Be it known that I, JOHN KREIBICH, a citizen of the United States, residing at the city of Philadelphia, in the county of Philadelphia and State of Pennsylvania, have invented certain new and useful Improvements in Spring-Controlled Draw-Off Cocks for Liquid-Containers, of which the following is a specification.

10 My invention has relation to a spring controlled draw-off valve cock for a liquid container, for root beer, lemonade or the like; and in such connection it relates particularly to the constructive arrangement of such a cock for the defined purpose. It is highly desirable in such a container to provide the same with a draw-off cock which is susceptible of being readily applied and in a handy and quick manner manipulated to 15 prevent wasteful discharge and also so as not to be so affected by any pressure exerted to operate the same, as to cause the cracking of the container.

The arrangement of the cock according to 25 my invention embodies such features as mentioned; and to that end my invention consists of a draw-off valve cock constructively arranged in substantially the manner hereinafter described and claimed.

30 In the accompanying drawing is illustrated in vertical longitudinal section, a draw-off valve cock embodying main features of my said invention in application to so much of what represents a liquid container as will serve to exemplify the application of such a cock thereto.

Referring to the drawings 3 is a portion 40 of a glass container as shown in broken section to receive and dispense lemonade, root-beer or the like therefrom.

45 4, is the spring-controlled draw-off valve cock of the character of my invention, which as shown is in an operative relation in connection with a liquid container 3. The cock 4, is provided with a longitudinal barrel 5, having at one end a depending vertical valve chamber 6, in which is screw threaded thereinto a cap 7, having an internal hollow and cone-shaped stem 7^a, with which cap en-

gages one end of a coiled spring 8, arranged 50 so as to encircle the hollow cone-shape stem 7^a, thereof, and the opposite end of the said spring 8, engaging the head 9^a, of a perforated valve 9, having a spindle extending therefrom and arranged to play in normal 55 use up and down within the hollow of the cone-shaped stem 7^a, of the cap 7, under the influence of the coil-spring 8, when the valve 9, is shifted in the said chamber 6, in a manner for example, as hereinafter more fully 60 explained. The perforation 9^b, of the valve 9, is arranged to register with the bore of the barrel 5. The valve chamber 6, is offset at 6^a, to receive a gasket 6^c, of the valve head 9^a, so as to establish a tight joint under 65 the tension of the spring 8, with the bore of the barrel 5, from the container 3, and chamber 6 thereof, when the vertical valve is not in use. The barrel 5, is provided beneath the same with a recessed guide 10 70 and a slotted bearing 11, to pivot a connecting rod 12, thereto and to guide the same in the recessed guide 10, in connection with the vertical perforated valve 9, normally closing the registering opening of the barrel 75 under the tension of the coiled spring 8, in order that by a slight hand or other pressure exerted against the connecting rod 12, in an upward direction the valve 9, can be elevated to cause the perforation 9^b, to wholly 80 or partially register with the internal bore of the barrel 5, and thus to permit of a variable discharge from the liquid container 3, into any suitable receptacle, for use.

Having thus described the nature and objects of my invention, what I claim as new and desire to secure by Letters Patent is:—

A draw-off cock, comprising a barrel having a valve-chamber, a removable cap for the chamber provided with a hollow cone-shaped stem, a tubular perforated valve, operatively arranged in said chamber and provided with a head having a spindle arranged to engage in the hollow of the cone-shaped stem of said cap and the perforation 90 of said valve to register with the bore of said barrel, a spring coiled about said cone shaped stem and bearing against the head of 95

said spindle to hold said valve normally in a closed relation and a rod connected with said barrel and valve and arranged longitudinally thereof, for manually operating the latter, substantially as and for the purposes described.

In witness whereof, I have hereunto set

my signature in the presence of two subscribing witnesses.

JOHN KREIBICH.
